(57) **CLAIM**

The ornamental design for a connector as shown and described.

DESCRIPTION

FIG. 1 is a front top perspective view of a connector showing our new design;

FIG. 2 is a rear top perspective view thereof;

FIG. 3 is a front bottom perspective view thereof;

FIG. 4 is a top view thereof;

FIG. 5 is a bottom view thereof;

FIG. 6 is a right side view thereof;

FIG. 7 is a left side view thereof;

FIG. 8 is a front view thereof; and,

FIG. 9 is a rear view thereof.

The uneven-length broken lines immediately adjacent to the shaded areas define the bounds of the claimed design and form no part thereof. The even-length broken line portion of the figure drawings depict portions of the connector that form no part of the claimed design.
